UNITED STATES PATENT OFFICE

CARL BUSCH THORNE, OF HAWKESBURY, ONTARIO, CANADA

LOG BARKER

Application filed October 22, 1928. Serial No. 314,248.

The invention relates to a log barker, as described in the present specification and illustrated in the accompanying drawings that form part of the same.

5 The invention consists essentially of the novel features of construction pointed out broadly and specifically in the claims for novelty following a description containing an explanation in detail of an acceptable 10 form of the invention.

The objects of the invention are to maintain a steady mechanical drive of the logs through a pocket or on a carrier or other means of support, and during this mechanical drive keep the logs parallel to one another and raise, lower, roll and lengthwise 15 tilt them and so disturb the logs to such an extent as will insure a good rubbing for the removal of the bark; to insure a steady and 20 large output from any one installation of barkers, and thereby increase the turnover of a mill particularly in the production of pulp for paper and silk manufactures; to maintain the barking machine at a reasonable 25 cost by the use of waste steam, air or other expansile fluid in the operation of the many reciprocating members; and generally to provide a durable, economical and efficient 30 means of stripping the logs of their bark covering.

In the drawings, Figure 1 is a longitudinal sectional view of a plurality of reciprocating members operating in a confined area.

Figure 2 is a plan view of the invention as 35 illustrated in Figure 1.

Figure 3 is a side elevational view of the same form of mechanical, driving and agitating means applied to a conveyer system 40 for the continuous operation of rubbing and conveying between the feed and the discharge end, and showing retaining and retarding chains.

Figure 4 is a sectional detail of the valve 45 casing and intake connections.

Figure 5 is a plan view of the invention as illustrated in Figure 3.

Figure 6 is a detail of the connections and feed of the driving fluid.

Figure 7 is a sectional detail of a pocket 50 showing the combined use of the driving means with an agitating cam.

Like numerals of reference indicate corresponding parts in the various figures.

Referring to the drawings, the numeral 10 55 indicates a plurality of cylinders leaning forwardly and suitably supported in a frame 11, and having the intakes 12 and the exhaust ports 13, the said frame 11 forming a part of the structure of a pocket 14, this pocket being 60 of considerable length and having the inclined way 15, forming the front wall, and the inclined way 16 forming the rear wall and leading to the runway 17.

The plungers 18 reciprocate in the cylinders 10 and the logs are piled along the bottom of the pocket on top of these plungers.

The cylinder 19 and plunger 20 operating therein are situated beyond the end of the pocket and the plunger operates through the 70 opening 21 in the rear wall, said cylinder 19 having also an intake and exhaust.

The cylinders and plungers extend in a central line under the bottom 22 of the pocket, which has a longitudinal slot 23, through 75 which the plungers project into the pocket.

These plungers are normally held down by the pile of logs, but on applying expansile fluid, such as steam, air or other fluid, force, the plungers operate against the logs, of course there may be one, two, three or more rows of plungers as desired, but only one row is shown here to illustrate the invention.

The intakes 12 are connected in the desired order of operation to the ports 24 in the valve casing 25, and inside the valve casing a rotary valve 26 is operated, said rotary valve being mounted on the shaft 27, which extends 85 90

through the reduction gear 28 to the motor 29, or to any other suitable power.

The valve is journalled in the bearings 30 in the valve casing and in the valve casing head 31 to which the feed pipe 32 is secured, 5 said feed pipe communicating with the interior of the valve casing and valve through the port 33 in said head, thus the many plungers may be operated in any manner desired by the operator, as it is all a matter of 10 selecting ports for the several intakes, consequently the disturbance of the logs by the movement of the plungers is varied in order to secure the most efficient upheaval of the pile for rubbing purposes.

15 In so far as the plunger 20 is concerned, it is timed to operate at certain intervals in order that logs may be regularly lifted to the runway 17, and thus keep the continuous operation of the barking machine in proper order.

20 In Figure 3 the sides of the pocket may be in the form of rollers, and these rollers 34 are shown in vertical arrangement and pivotally secured at their upper and lower ends, 5 so that the progress of the logs in the pocket will be much facilitated.

25 In Figures 3 and 5 another means is shown of using this mechanical driving and disturbing means, in which the cylinders 35 are arranged in a plurality of rows forming the real support of the logs.

30 The plungers 36 engage the logs and keep moving the pile forwardly and at the same time upheaving them.

35 The inclined way 37 forms the feed end and the inclined way 38 forms the discharge end and the logs are retained at the upper end by the chains 39, and chains 40 are also stretched 40 along the bottom between the plungers while the side guides 41 or other guide rolls serve to help the pile in a continuous movement forwardly.

45 In this form of the invention the main idea is to eliminate the pocket where such structures are inconvenient and simply to retain the pile of logs together for a sufficient period to accomplish the purpose of the disturbance, that is to say, to strip the bark off, of course it may be advisable to use cams to 50 create part of the disturbance, or to facilitate the delivery or even to help in the feed so long as the essential feature of the invention, that is to say, the rubbing of the logs is done 55 with success.

60 In the operation of this invention the logs are fed to the entrance of the disturbed area and piled up in said area until there is a considerable depth of logs, and this feed is continued, and during the period while the logs are in the disturbed area they are continually pushed and driven forwardly at various points by the several plungers, thus the pile presents an appearance of continuous upheaval so that they roll against one another

70 backwards and forwards, until the bark is rubbed off by the time that they reach the end of the disturbed area or by the time they have been in the disturbed area long enough they are delivered on to a runway and discharged and ready for whatever manufacture they are to be employed in.

75 It will be noticed that in Figures 3 and 4 the cylinders are perceptibly dipped in the centre to give the disturbed area a dish-like form, so that while they are being driven forwardly there is always an inclination for the logs to meet in the centre and this serves to retard them from too quick delivery, but there may be many ways of confining the logs 80 long enough for stripping purposes, and it is only for clearness in description of the invention that two ways have been shown and described.

85 It has been mentioned that the present driving means may be used with an agitating cam, so this has been shown in Figure 6, in which the cam 42 does the agitating while the driving means helps the logs outwardly.

90 What I claim is:

1. In a log barker, a log receptacle, a plurality of forwardly inclined cylinders and plungers operating therein and forming the bottom of said receptacle and means for operating the plungers at varying intervals respectively into contact with a pile of logs and tumbling said logs into rubbing contact.

95 2. In a log barker, a plurality of endless chains engaging the pile of logs and moving them forwardly, disturbing cams suitably operated, and supplementary disturbing means engaging the logs and pushing them in a forward direction.

100 3. In a log barker, chain conveyers adapted to support a pile of logs between a feed chute and delivery chute, plungers reciprocated in forwardly inclined cylinders between said chains and varying in respect to the timing of the forward strokes of the several plungers and a chain extended over the pile of logs and in contact therewith and restricting the ingress and egress openings to the conveyers.

105 4. A log barker comprising a log support, plungers operating through said support and disturbing said logs, cylinders having intakes and exhaust ports and containing said plungers, and a valve casing having ports connected to the several intakes and having an inlet port and a valve in said casing having a port registering with said ports by selection.

110 5. In a log barker, a row of projectile members forming supports under a pile of logs and aimed in a forward direction in respect to the movement of the logs and means for shooting said projectiles and coincidentally rolling and driving said logs.

115 6. In a log barker, a log pocket and a longitudinal row of reciprocating members suit-

ably driven and forming supports and forwarding members in maintaining the constant onward movement during stripping.

7. In a log barker, a log pocket having feed and discharge ends, a fixed chain member laying over the logs and means for projecting the logs against said chain member and coincidentally rolling them together and onwardly at the same time.

10. Signed at Montreal, Canada, this 20th day of September, 1928.
